UNITED STATES PATENT OFFICE.

DANIEL MOYER, OF ALLENTOWN, PENNSYLVANIA, ASSIGNOR OF ONE-HALF
TO FREDERICK CONLIN, OF BETHLEHEM, PENNSYLVANIA.

TROLLEY-STAND.

SPECIFICATION forming part of Letters Patent No. 618,231, dated January 24, 1899.

Application filed April 12, 1898. Serial No. 677,349. (No model.)

To all whom it may concern:

Be it known that I, DANIEL MOYER, a citizen of the United States, residing at Allentown, in the county of Lehigh, State of Pennsylvania, 5 have invented certain new and useful Improvements in Trolley-Stands, of which the following is a specification, reference being had therein to the accompanying drawings.

This invention relates to trolley-stands, and 10 is particularly adapted for use in connection with the trolley-pole used to establish electric contact with an overhead conductor supplying current for an electric railway.

The invention has for its object to provide 15 an improved construction by which the stand may be completely reversed and in which independent means are used to produce the necessary tension upon the trolley-pole.

The invention has for a further object to 20 relieve the tension devices from all strain when the pole is in a vertical position and to bring into operation only one set of tension devices when the pole is in use, whereby in the event of a breakage of the parts the pole 25 may be reversed and the opposite set of tension devices brought into operation.

A further object is to provide a construction 20 by which the pole may be depressed into a substantially horizontal position in order 30 to pass beneath a low bridge or car-barn door.

Other objects and advantages of the invention will hereinafter appear in the following description, and the novel features thereof will be particularly pointed out in the appended claims.

In the drawings, Figure 1 is a side elevation 35 of the trolley-stand. Fig. 2 is an end elevation of the same. Fig. 3 is a detail perspective of the levers carried by the pole-socket, 40 and Fig. 4 is a detail horizontal section showing the means for securing the pivoted frame upon the post carried by the car-roof.

Like letters of reference indicate like parts throughout the several figures of the drawings.

The letter A designates a base secured to the roof or other portion of a car in any suitable manner and provided with an upwardly extending post A'. This post is provided ad- 45 jacent to its upper portion with an annular

groove A² and forms a pivotal support for the block B, which carries the oppositely-extending supporting-frames B'. These frames are secured to the block B by any suitable means—for instance, bolts B²—and the opposite ends of the frames B' are provided with sockets B³. The block B is pivotally mounted upon the post A' and secured against vertical movement thereon by any suitable means passing through the block and the groove A² 55 in the post A'—for instance, a split pin a. The trolley-pole socket C is pivoted in the upper portion of said block B by any suitable means—for instance, by a pivot-pin C' passing through the block and extending beyond 60 the opposite ends of the socket. The lower portion of this socket is provided with forked extensions constituting levers C², said levers being provided with lateral extensions C³ at 65 their lower ends, from which pins or lugs C⁴ extend inwardly at one end, and similar pins or lugs C⁵ extend outwardly at the opposite end. The levers C² are provided with pivoting-apertures C⁶ for the reception of the pivot-bolt C', and the upper end of the socket is 70 adapted to receive the trolley-pole C⁷, which is secured in position by any usual means—for instance, set-screws C⁸.

Upon the pivot-bolt C', between the post B and levers C², there are located opposite tension-arms D, while beyond the outer face of the levers C² a similar set of opposite tension-arms D' are provided. The lower ends of these arms are connected with any suitable tension devices—for instance, a spring E— 80 which may be connected to the arms by means of an interposed link E' and to the frame B' by means of an adjusting-bolt E², passing through the sockets B³ and adapted to be adjusted by means of a nut E³, bearing against 85 the outer face of said sockets. Similar springs are connected to each of the arms, and each set of springs is connected to a cross-bar E⁴, which is removably attached to the adjusting-bolt E² by means of a bolt e. The springs E are 90 connected to the inner set of arms D and are attached to the cross-bar E⁴ at one end of the stand—for instance, the left end, as shown in Figs. 1 and 2—and the battery of tension-springs connected to the opposite outer arms 95 100

D' are connected to the cross-bar E⁴ and adjusted by the bolt E² at the right end of the machine. It will be observed that when the pole is in a vertical position, as shown in Fig. 1, the springs are relieved from all tension, save that of their adjusting-bolts, while as soon as the pole is depressed for engagement with the trolley-wire—for instance, toward the right of Fig. 1—the pins or lugs C⁵ upon the opposite levers C² will engage the opposite outer tension-arms D' and bring the trolley-pole under the tension of the springs at the right end of the stand. When it is desired to depress the pole to more than the normal extent, the spring E will yield and permit such depression until the pole is in a substantially horizontal position. The tension of the springs will be regulated and adjusted by means of the nuts E³, so as to exercise the desired pressure upon the trolley-pole. When it is desired to reverse the trolley-pole either at the end of a trip or by reason of injury to the springs or tension-arms, it is simply necessary to swing the frame upon its pivotal support to bring the opposite battery of springs connected to the arms D into the position previously occupied by the other end of the stand. This reversal is not necessary in the ordinary use of the stand, as it will be seen that the socket can be depressed in either direction, and if depressed toward the left the arms D will engage the pins C⁴ and act in the manner just described in connection with the arms D'. A trolley-stand is thus provided which guards against all delay incident to a breakage of the tension devices and which is capable of use without the necessity of reversing the stand when the direction of incline of the trolley-pole is changed. The use of the independent springs for governing the tension upon the pole obviates all the disadvantages occasioned by the breakage of the single spring used in a number of previous constructions.

It is obvious that numerous changes may be made in the details of construction without departing from the spirit of the invention, as defined by the appended claims.

Having described my invention, what I claim, and desire to secure by Letters Patent, is—

1. In a trolley-stand, the combination with a pivoted pole-socket provided with a lever, a pivoted arm mounted to oscillate independently of said lever, a device carried by said lever to engage said arm when the lever is moved in one direction, and tension means for retaining said arm in one position; substantially as specified.
2. In a trolley-stand, the combination with a pivoted pole-socket provided with a lever, a pivoted arm mounted to oscillate independently of said lever, a device carried by said lever to engage said arm when the lever is moved in one direction, tension means for retaining said arm in one direction; and means

for adjusting said tension; substantially as specified.

3. In a trolley-stand, the combination with a pivoted pole-socket provided with a lever, 70 a pivoted arm mounted to oscillate independently of said lever, a device carried by said lever to engage said arm when the lever is moved in one direction, and a spring extending from said arm and an adjacent frame; 75 substantially as specified.

4. In a trolley-stand, the combination with a pivoted pole-socket provided with a lever, projections from the opposite faces of said 80 lever, pivoted arms upon opposite sides of said lever, and independent means for holding each of said arms under tension; substantially as specified.

5. In a trolley-stand, the combination with a pivoted pole-socket provided with a lever, 85 projections from the opposite faces of said lever, pivoted arms upon opposite sides of said lever, a frame, and springs extending between said arms and the opposite ends of said frame to exert tension upon the arms in 90 opposite directions; substantially as specified.

6. In a trolley-stand, the combination with a pole-socket provided with a pivoted forked lower end constituting levers, lateral extensions upon said levers, inwardly-extending 95 projections upon one end of said extensions and outwardly-extending projections upon the opposite end, oppositely-located arms lying within the levers, springs connecting said arms with a frame, oppositely-located 100 arms upon the outside of said levers, and springs connecting said arms with the opposite end of said frame; substantially as specified.

7. In a trolley-stand, the combination with 105 a pole-socket provided with a pivoted forked lower end constituting levers, lateral extensions upon said levers, inwardly-extending projections upon one end of said extensions and outwardly-extending projections upon 110 the opposite end, oppositely-located arms lying within the levers, springs connecting said arms with a frame, oppositely-located arms upon the outside of said levers, springs connecting said arms with the opposite end of 115 said frame, a cross-bar connected to the ends of each set of said springs, and adjusting-bolts through the opposite ends of said frame and engaging said cross-bars; substantially as specified.

8. In a trolley-stand, the combination with a securing-base provided with a vertically-extending post having an annular groove therein, of a bearing-block provided with a socket to fit said post and a lateral pivoting-recess above said socket, means to secure said block against vertical movement on the post, a pole-socket provided with a lever, a pivot-pin passing through said recess and pole-socket, supporting-frames at opposite sides 130 of said block, an arm mounted to oscillate independently of said lever, a device carried by

said lever to engage said arm, and means carried by said frame for exerting tension upon said arm; substantially as specified.

9. In a trolley-stand, the combination with 5 a vertically-extending post having an annular groove therein, of a bearing-block located upon said post, means to secure said block against vertical movement on the post, a frame extending from said block, a pole-socket pivoted to said post, a lever depending from said socket and provided with a projection, a pivoted arm mounted to oscillate independently of said lever, and a spring connecting said arm with the frame; substantially as specified.

10 15 10. In a trolley-stand, the combination with

a bearing-block, of a pivoting-bolt located in the upper portion thereof, a pole-socket pivoted upon said bolt and provided at its lower end with levers having oppositely-located projections, arms pivoted upon said bolt between said block and levers, arms pivoted upon said bolt outside of said levers, and independent means for exerting tension in opposite directions upon each set of said arms; substantially as specified.

20 25 In testimony whereof I affix my signature in presence of two witnesses.

DANIEL MOYER.
